UNITED STATES PATENT OFFICE

WILLIAM J. PANNIER, JR., OF BELLEVUE, AND OSCAR M. PANNIER, OF KILBUCK TOWNSHIP, ALLEGHENY COUNTY, PENNSYLVANIA, ASSIGNEES TO PANNIER BROTHERS STAMP COMPANY, OF PITTSBURGH, PENNSYLVANIA, A CORPORATION OF PENNSYLVANIA

HAMMER STAMP

Application filed April 15, 1929. Serial No. 355,125.

Our invention refers to an improvement in hammer stamps for the purpose of stamping sheet metal or any other similar commodity having a substantially flat surface, against which a stamp may be thrust for imparting thereon, in the manner of a hammer, having an operating handle. In such stamps, it is desirable that there be interposed between the handle and the stamping face a sufficient degree of resiliency adapting the face of the stamp to effect good contact, independent of variations in exact parallelism between the surface to be stamped and the stamping surface, when used. 10 The device consists generally of a stamp, in either single or double form, having an operating handle so connected as to permit of a limited degree of flexibility whereby to compensate for any lack of accuracy in delivering the blow so as to allow the stamping face to automatically adjust itself, under the impulse of the blow.

In its construction, our stamp is composed of a single or double head portion composed of rubber or other suitable resilient or flexible material, a handle and means connecting it with the stamping member or members, together with detachable stamping heads secured thereto. Such heads are 20 also of rubber having on their faces any desired imprinting characters and are provided with an inner reinforcing plate and securing studs.

A feature of special importance and value 25 in the present invention is in the combination with the main stamp of an additional laterally arranged stamp or stamps capable of being secured between the main head and the stamping head, for additional or separate stamping operations, with certain other features of construction and advantage, as shall be more fully hereinafter described.

The device is in its principal elements 30 similar to that shown in a companion application filed herewith Ser. No. 355,124.

Referring to the drawings showing one preferred construction:

Fig. 1 is a view in side elevation, showing 35 the double head form of stamp complete;

Fig. 2 is a plan view of the upper stamping face thereof;

Fig. 3 is a similar view of the opposite or lower stamping face.

Fig. 4 is an enlarged cross sectional view 55 on the line IV—IV of Fig. 1.

Fig. 5 is a perspective view showing the face of the main stamping head.

In the drawings, the main inner portion of the stamp is in the form of a main hammer head 2 of rubber or the like having an enlarged outer body of circular or other form adapting it to receive and be secured to the detachable stamping head 2b.

The body portion of the head 2 may be 60 of any suitable form, and is provided with an inner diminishing or narrowed neck 6 having a flat opposing face for attachment to and connection with the end 7 of an operating handle 8. A central connecting bolt 65 9 is imbedded and vulcanized by its head and shank portion within the middle of one of the heads 2 and projects sufficiently far beyond its smaller attaching face to extend through a registering hole in the end of the 70 handle and therebeyond, for attachment to the companion head 2a at the opposite side, as in Fig. 4.

In such construction the opposite head 2a is generally similar to head 2 above described, but is provided with a centrally imbedded and vulcanized sleeve nut 11 of any 75 suitable form.

The nut 11 makes screw engagement with the threaded outer end of bolt 9 by turning 80 and tightening thereon, by which the two heads are tightly clamped together and against the opposite side faces of the handle terminal 7. By such construction head 2a 85 may be readily connected to or disconnected from the other head 2, for substitution as to one or both, of other similar heads of different size or for any other purpose.

By such construction the comparatively 90 soft rubber body of the heads surrounding the bolt and nut respectively provides ample 95 flexibility to adapt the face of either supplemental stamping head 2b to make a good stamping impression, whether brought fairly and evenly against the surface to be stamped, 100

or at a considerable angle thereto, by the operator.

When there is any such variation and the face of either head is brought against a surface with which it would not ordinarily register, due to any angular relation, the flexibility of the head connection with the handle permits of automatic adjustment and good stamping results, under impact of the blow.

- 10 The supplemental stamping head 2b at either side is provided with any suitable printing letters, figures or characters, as indicated on the face views, Figs. 2 and 3. 15 Such characters are ordinarily molded in the rubber, as at 3, or may be in the form of detachable inserted type 4, all mounted on a common plane.

For the purpose of reinforcing the head 2b 20 closely adjacent to the area embodying such characters, and for providing a substantial attaching base, the head 2b is provided with a thin reinforcing disk or plate 5. Such plate is tightly secured to the inner face of 25 head 2b by any suitable means as cementing, vulcanizing, etc., and may be of copper, brass, or other suitable material.

Heads 2 and 2a are each provided with transverse reinforced bolt holes having inserted tubular lining sleeves 13 extending 30 through from one side to the other, as in Fig. 4. Head 2b is provided with a corresponding series of similarly located and spaced connecting bolts 14 having enlarged 35 reinforcing beveled heads 15, the flat inner ends of which are soldered or welded to the face of plate 5. The outer ends of sleeves 13 are inwardly beveled to receive heads 15, so that when the stamping head 2b is in 40 position, the parts fit snugly and tightly together, and are held by the securing nuts 16.

One advantage of the comparatively thin plate 5 when tightly secured to the stamping head 2b is that it may be readily bent 45 to a concave form for attachment to the convex face of the main head or base, as in making a rocker stamp, capable of rolling motion over the surface being stamped.

By such construction it will be seen that 50 a supplemental head may be substituted for another at either side, having any suitable or different form, kind, or arrangement of stamping characters, either molded in the rubber face of the head itself, or separately 55 attached as by the stamping characters 4a.

The latter may be of the split wedge type like that shown in prior patent of W. J. Pannier, Jr., No. 1,191,820. In such case their divided bases bear against the inner 60 socketed surface of the head, closely adjacent to plate 5, providing a sufficiently firm and comparatively rigid opposing bearing.

For the purpose of providing a lateral 65 stamp or stamps, arranged at right angles

to the main stamping face, we provide the projecting stamping member or element 17 of any suitable kind, as rubber or metal, having an attaching plate 18 secured to flange terminal 19 of bar 20, as by bolts 70 21. Bar 20 is imbedded across the face of head 2, flush with its attaching surface, and snugly mounted within a receiving channel or groove 22 extending across the face, preferably in line with one pair of bolts.

At the locations of the bolts the bar 20 is cut out in circular or other form and surrounds a boss or extending portion 23 of the main base, which projects through an opening 24 of the bar, as shown.

By such construction the bar 20 is maintained fixedly in position against either lateral or longitudinal shifting, and when the stamping head 2b is in position, also against outward movement.

As thus constructed either of the stamping surfaces may be applied by merely adjusting the grasping hold on the handle.

Either of the stamping heads 2b or 17 may be removed and substituted by others quickly 90 and easily, or the main stamping heads 2 or 2a may be used with the handle, either singly or double, and the device provides for quick and complete application of a great variety of marking.

The construction and operation of the invention will be readily understood and appreciated by all those familiar with hand operated stamping devices. It is comparatively simple in construction, capable of easy and rapid change or substitution, and may be used at considerable speed by alternately striking upon an inking pad and then upon a surface to be marked, without the necessity for any special skill.

The device is extremely useful, very durable, and may be made in different shapes, designs, sizes, weights, or otherwise changed or varied by the skilled mechanic, but all such changes are to be understood as within the scope of the following claims.

What we claim is:

1. A hammer stamp consisting of a main head provided with a separable stamping head secured to its face and a laterally extending stamping head held between said heads.

2. A hammer stamp consisting of a main head provided with a separable stamping head secured to its face and a laterally extending stamping head held between said heads, and a handle secured to the main head.

3. A hammer stamp consisting of a main head provided with a separable stamping head secured to its face and a laterally extending stamping head held between said heads and provided with a separable stamping unit.

4. The combination with a main stamping head and a separable stamping head secured

thereto, of an intervening bar having a laterally extending stamping unit.

5. The combination with a main stamping head and a separable stamping head secured thereto, of an intervening bar having an attaching face thereon and a stamping unit separably attached thereto.

10. In combination, a main head having a handle and a flat face, a stamping head secured thereon, a transverse bar extending across between the main head and the stamping head having a projecting base, and a stamping unit on said base.

15. In combination, a main head having a flat face and a recess therein, a bolt socket extending through the head having a surrounding abutment flush with the flat face, a stamping bar mounted in the recess having an opening engaging said abutment, and 20 means for holding the stamping bar having a bolt engaging the socket.

25. In combination, a main head having a flat face and a recess therein, a bolt socket extending through the head having a surrounding abutment flush with the flat face, a stamping bar mounted in the recess having an opening engaging said abutment, and a stamping head fitting against the face of the main head and the stamping bar having a 30 holding bolt extending through the bolt socket and clamping it directly against the main head and the stamping bar.

35. In combination, a main flexible stamping head provided with a flat attaching face having a plurality of transverse bolt openings, a transverse slot across the face of the head, a bar therein having a terminal flange, a stamping unit secured thereon, and a stamping head having a series of holding bolts extending through the bolt openings 40 and confining the bar in its slot.

45. In combination, a main flexible stamping head provided with a flat attaching face having a plurality of transverse bolt openings, a transverse slot across the face of the head, a bar therein having a terminal flange, a stamping unit secured thereon, and a stamping head having a holding bolt extending through the bar and one of said bolt openings and confining the bar in its slot.

50. 11. In combination with a main head having a flat attaching face and a transverse slot therein, integral abutments of the head extending through the slot to the plane of the attaching face, a bar laid in the slot having laterally extending stamping heads, and a stamping head having holding bolts extending through the main head and said abutments.

55. 12. In combination with a main head having a flat attaching face and a transverse slot therein, integral abutments of the head extending through the slot to the plane of the attaching face, reinforcing sleeves therein, a bar laid in the slot having laterally extend-

ing stamping heads and clearance openings for the abutments, and a stamping head having holding bolts extending through the main head and said abutments.

60. In testimony whereof we hereunto affix our 70 signatures.

WILLIAM J. PANNIER, JR.
OSCAR M. PANNIER.
